UNITED STATES PATENT OFFICE.

ANDREW J. ROSS AND MARSHALL J. MORTON, OF PIONEER, CALIFORNIA;
SAID MORTON ASSIGNOR TO SAID ROSS.

PUMP.

No. 837,342.

Specification of Letters Patent.

Patented Dec. 4, 1906.

Application filed August 5, 1905. Serial No. 272,847.

To all whom it may concern:

Be it known that we, ANDREW J. ROSS and MARSHALL J. MORTON, citizens of the United States of America, and residents of Pioneer, county of Kern, State of California, have invented certain new and useful Improvements in Pumps, of which the following is a full and clear specification, reference being had to the accompanying drawings, in which—

10 Figure 1 is a side elevation, and Fig. 2 a plan view, of our improved pump; Figs. 3, 4, and 5, vertical longitudinal sectional views showing the oscillating cylinder in different positions; Fig. 6, a vertical transverse section on the line 6 6 of Fig. 1; Fig. 7, a vertical section on the line 7 7 of Fig. 3; Figs. 8, 9, and 10, details showing more particularly the arrangement of ports.

20 The object of this invention is to provide a simple and powerful apparatus which will furnish a continuous stream of water at a high pressure, as more fully hereinafter set forth.

25 To the accomplishment of this object and such others as may hereinafter appear the invention consists of the parts and combination of parts hereinafter fully described, and particularly pointed out in the appended claims, reference being had to the accompanying drawings, forming a part of this specification, in which the same reference characters designate like parts throughout the several views.

35 Referring to the drawings by reference characters, A designates a double pump-cylinder mounted to oscillate upon a horizontal transverse bolt 1, which passes through a partition a' at the center of the cylinder and through supporting-disks E E' and is provided with a tightening-nut 2, said disks being 40 stationarily mounted upon pedestals S, to which they are rigidly secured by bolts s. The disk E is provided with a central bolt-hole e^5 and with segmental ports e^3 e^4 , and the disk E' is provided with a central bolt-hole e^6 and a similar pair of ports e' and e^2 . The ports in disk E are just below the horizontal center of the disk, while the ports in the disk E' are just above the center.

45 Bolted to the outer face of disk E is a chamber F, adapted to be connected by its elbow f to a supply-pipe or a delivery-pipe and provided with flanges f^3 , by which it is bolted to the face of the disk over the ports e^3 and e^4 , this chamber being provided with a recess or depression f^4 in order to straddle the nut 2. Bolted to the outer face of the

disk E' is a similar casing F', which is provided with a recess f^5 to straddle the head of bolt 1, flanges f^2 , by which it is bolted to the disk, and an elbow part f' , by which it is connected to the delivery or the supply pipe, according as this chamber is used as an exhaust or a supply chamber. This chamber F' connects with the ports e' and e^2 . Mounted to turn on the disks E E' are a pair of similarly-shaped disks D D', flanged at d^6 and d^{10} , respectively, to embrace the stationary disks, and provided with central holes d^7 d^8 , respectively, for the passage of the central bolt 1. These disks D and D' are grooved to receive 7c the cylinder A and are clamped thereon by four transverse double-ended bolts x.

50 The cylinder A is provided with segmental ports a^3 and a^5 at one side of the partition a' and with similar ports a^2 at the opposite side 75 of the partition a' . The ports a^3 a^5 register with ports d^2 d^4 in the oscillating disks, and when the cylinder is oscillated these ports are adapted to alternately register with the ports e^2 e^3 in the stationary disks. The corresponding ports a^2 in the cylinder register with ports d^2 in the oscillating disks, and these ports d^2 are adapted to alternately register with the ports e' e^4 when the cylinder is oscillated. The cylinder is provided at each end 80 with a stuffing-box a, and working in each end of the cylinder through its stuffing-box is a ram-piston B. These two pistons are connected to work in unison by cross-heads b b' and connecting-rods b². Attached to one 90 of the pistons is a bracket-bearing c², in which is journaled a crank-pin carried by a crank c', this crank being carried by a shaft c, journaled in bearings m of a pair of pedestals M, said shaft carrying a driving-pulley C 95 or other means for driving it.

55 It will be observed that when the shaft c' is driven the pistons will be alternately forced in and drawn out of the opposite ends of the cylinder and the cylinder will be oscillated 100 to permit these movements of the pistons. The oscillation of the cylinder will cause the ports to alternately register with the inlet and outlet chambers, thereby alternately filling and discharging the cylinders, keeping up 105 a continuous discharge of liquid. This pump, as will be observed, is especially adapted for use where a large supply under a powerful head is desired.

60 It will be apparent to those skilled in the art that various mechanical embodiments of the invention are possible, and we therefore

do not wish to be limited to the exact arrangement and construction shown.

What we claim, and desire to secure by Letters Patent, is—

- 5 1. In an apparatus of the class described, the combination of a pair of supporting-disks stationarily mounted and provided each with a pair of inlet-ports, one pair being above the center and the other below, an oscillating disk mounted on each of said stationary disks, a double-ended cylinder mounted between said oscillating disks and divided midway its ends by a single imperforate partition, the cylinder and oscillating disks being
- 10 15 provided with ports adapted to alternately register with the ports in the stationary disks, the ports in the cylinder being at opposite sides of the same and also on opposite sides of said partition, a piston working in each 20 end of the cylinder, means connecting these pistons, and means for oscillating the cylinder and reciprocating the pistons, substantially as set forth.
- 25 2. In a pump the combination of an oscillating double-ended cylinder having an imperforate partition midway its ends, means for pivotally supporting the cylinder, a piston working in each end of the cylinder, means connecting these pistons, means for 30 reciprocating the pistons simultaneously in opposite directions and simultaneously oscillating the cylinder, and supply and exhaust

ports for each end of the cylinder, these ports being at opposite sides of the cylinder and also at opposite sides of the partition.

3. The combination of a pair of supporting-disks each provided with a pair of ports, the ports in one disk being above the center and the ports in the other disk being below the center, an oscillating disk mounted on each of said stationary disks and provided with a pair of ports adapted to register with the ports in the stationary disk, a double-ended cylinder mounted between said oscillating disks and divided midway its ends with an imperforate partition, the cylinder and oscillating disks being provided with ports adapted to alternately register with the ports in the stationary disk, means connecting the oscillating disks to clamp the same upon the cylinder, a piston working in each end of the cylinder, means connecting these pistons, and means for oscillating the cylinder and simultaneously reciprocating the pistons.

In testimony whereof we hereunto affix our signatures, in the presence of two witnesses, this 28th day of July, 1905.

ANDREW J. ROSS.
MARSHALL J. MORTON.
